UNITED STATES PATENT OFFICE

RAYMOND C. FINCH, OF JAMESTOWN, NEW YORK, ASSIGNOR TO POSTINDEX COMPANY, INC., OF JAMESTOWN, NEW YORK, A CORPORATION OF MASSACHUSETTS

PAPER FILE

Application, filed January 9, 1930. Serial No. 419,572.

This invention relates to a novel paper file, in which the sheets are filed on sheet carriers supported by a mounting, and there is provided locking means to lock the sheet carriers to the mounting to prevent unauthorized removal of the sheet carriers therefrom. As shown, folded sheets arranged in overlapping relationship, with margins exposed to receive identifying matter, are perforated to receive sheet carriers in the form of flexible wires received in the folds of the sheets, passed through the perforations, and having terminal spacing enlargements received in channels presented by a panel, and there is provided a locking bar which extends transversely of and across the wires on the front of the wires, and through cut-outs in the sheets, while a lock provided with a key has a member which is movable into and out of the path of a portion of the bar. Unauthorized removal of any sheet is impossible without destruction thereof, but, by unlocking the lock and withdrawing the locking bar, any or all of the sheet carriers, with their attached sheets, may be removed for interchange, rearrangement and substitution or addition of carriers with new sheets on them.

The invention will be best understood by reference to the following description, when taken in connection with the accompanying drawings of one specific embodiment thereof, while its scope will be more particularly pointed out in the appended claims.

In the drawings:

Fig. 1 is a front elevation of a paper file exemplifying the invention, with the parts in their normal positions;

Fig. 2 is a front elevation of the file opened up, some of the sheets being directed upwardly, some downwardly, and others removed from their carriers, the better to illustrate the arrangement of the locking bar;

Fig. 3 is a rear elevation of the file, with a portion of the panel broken away, and with a part in section to illustrate the lock and the locking bar;

Fig. 4 is a sectional view, on an enlarged scale, on line 4—4 of Fig. 1;

Fig. 5 is a sectional view, on an enlarged scale, on line 5—5 of Fig. 3;

Fig. 6 is a sectional view, on an enlarged scale, on line 6—6 of Fig. 2, but with portions broken out to reduce the width of the figure;

Fig. 7 is a sectional view on line 7—7 of Fig. 6;

Fig. 8 is a sectional view, on an enlarged scale, on line 8—8 of Fig. 2;

Fig. 9 is an elevation of a sheet carrier and a sheet, the latter being unfolded and spread out flat, the better to illustrate the perforations through which the sheet carrier extends, and the arrangement by which the sheet and its carrier are interlocked with each other;

Fig. 10 is an elevation of one of the sheet carriers with its sheet, the latter being folded as in its normal condition.

Referring to the drawings and to the embodiment of the invention which is illustrated therein, and having reference at first more particularly to Fig. 3, there is shown a paper file comprising a mounting conveniently in the form of a sheet-metal panel 11, which, as shown in Fig. 6, presents sheet-carrier guides having channels 13, beneath or behind inwardly-directed, lateral flanges 14. As shown, the panel is also provided with transverse upper and lower, inwardly-directed flanges 15 and 16 (see Fig. 1), which close the upper and lower ends of the channels. Referring again to Fig. 6, the channels present guides for appropriate sheet carriers which, in the present example, are resilient wires 17, having terminal spacing enlargements 18 to space the wires, and to predetermine the overlap or exposure of the margins of the sheets presently to be described.

Referring now to Figs. 9 and 10, one of the sheet carriers is shown with its sheet 19, the latter being provided with perforations 20, through which the carrier is passed, and a fold 21 which intersects the perforations and receives the principal portion of the wire. As shown in Fig. 1, the sheets are arranged in overlapping relationship, with exposed margins the width of which is determined by the transverse dimensions of the spacers 18. The carriers, with their attached sheets, are inserted into and removed from

the channels in the panel by springing the carriers to reduce their lengths.

The construction as thus far described is substantially in accordance with the disclosure of the patent to Quigley, No. 1,450,304, issued April 3, 1923. As shown in Figs. 1 and 2, there is provided a hinged metal plate 21, which in its normal position, shown in Fig. 1, is directed upwardly or inwardly, 10 and overlies the lowermost sheet, but in the position shown in Fig. 2, is folded outwardly or downwardly to afford a sheet support and hand rest. This, however, has no particular connection with the present invention. 15 Referring now to Fig. 8, the upper end of the panel is equipped with a sloping sheet support 22, against which the uppermost sheet normally lies. This likewise has no necessary connection with the present invention, except in so far as it affords a housing 20 for the lock presently to be described, and this sheet support is secured to the panel, as by rivets 23, thus to protect the lock against tampering.

25 In the use of paper files, it is frequently desirable to prevent unauthorized removal of any of the records borne by the sheets. To this end, therefore, I have provided novel locking means now to be described, reference being had at first to Fig. 6. A locking bar 24, shown in cross-section in Fig. 6, extends transversely of and across the sheet carriers, and each sheet carrier is provided with a rearwardly or downwardly offset portion 25 to receive the bar. To make room for this offset portion, the panel 11 is likewise provided with a depressed or offset portion 26. To prevent the sheet carriers from turning in the channels and thus destroying 40 the proper relationship between their offset portions and the locking bar, the terminal enlargements 18 of the sheet carriers, as in the aforesaid Quigley patent, are only partially so, and 45 in Fig. 7, are shown as provided with slabbed-off parallel faces 27, which have a sliding fit in the channels, but do not permit the sheet carriers to rotate therein. The remaining cross-section of each enlargement, however, 50 is of cylindrical form to facilitate the spreading apart of two adjacent sheet carriers for the introduction of a third carrier between them.

The locking bar 24 is slidable lengthwise 55 into and out of the position which it normally occupies (see Fig. 2), and it extends through several guides. First of all, beginning at the top of the panel, the locking bar extends through an aperture 28 in the upper edge of 60 the panel, and it projects upwardly or outwardly a sufficient distance to enable it to be grasped, or at least to enable it to be engaged, by the user's thumb-nail, and for this purpose it is provided with a slight shoulder 29, 65 as shown in Figs. 2 and 8. By placing the

thumb-nail against the under side of this shoulder and pushing upwardly, the bar when unlocked may be moved lengthwise and withdrawn from its place. The lower end of the locking bar is received in a channel 30 (see Fig. 4) beneath or behind the flange 16. The locking rod is further received in a guide presented by a channel bar 31, shown in cross-section in Fig. 5, and secured as by welding in the depression 26 presented by the panel 11. The length of this channel bar is indicated in Figs. 2 and 8. To prevent the locking bar from being sprung outwardly or forwardly and thus to release its lower end from beneath the flange 16, I provide one or more, herein two brackets 33, which overlie the front face of the rod and are secured at their ends to the panel 11, as by rivets 34. These brackets, as shown in Fig. 6, have an offset formation, because the bar is a considerable distance 85 from the panel to which the ends of the brackets are secured.

The lock by which the locking bar is normally locked against removal will now be described. Referring to Fig. 3, there is shown a common form of lock 35, of a rather thin, flat type, having a rotatable cylinder 36 provided with a slot 37 for the introduction of a key (not shown), by which the lock may be operated in the same manner as the locks 90 of desks, cabinets and other things. This lock is suitably secured, as by rivets 38, to the panel 11. The lock has a usual bolt or locking member 39, which, in its normal position, is in the path of movement of a portion of the locking bar 24, and in the present example, the latter is provided with a notch 40, which receives the bolt. In case the user, after removing the bar, should reintroduce the same in a reversed position,—that is to say, with its other edge presented toward the lock, the bar may be, and herein is, provided with a second notch 41 in its other edge.

Referring again to the sheets (see Figs. 9 and 10), to afford ample room for the locking bar where it is received in the offset portion of the sheet carrier, the sheet is provided with a suitably shaped aperture 42, herein rectangular. This affords ample clearance, and prevents interference between the sheets and the locking bar. The sheet and its carrier are interlocked with each other, and with the locking bar, and inasmuch as the bar prevents springing of the sheet carriers, the latter cannot be sprung out of the channels 115 while the locking bar remains in its place.

It should now be evident that unauthorized removal of records is absolutely impossible without destroying the sheets or some of the mechanical parts which hold them in place. 125 On the other hand, when it becomes necessary or desirable to rearrange the records, or to remove some and to substitute others, this can readily be accomplished by simply unlocking the lock, removing the locking bar, and 130

then springing the sheet carriers out of their places.

The file may be used alone as shown, or it may be associated or combined with others in various ways, though in the example shown, it is intended to be connected edgewise to another similar file by a hinge comprising a pintle 43, extending through lugs 44, herein conveniently formed as integral parts of the panel.

Having thus described one embodiment of the invention, but without limiting myself thereto, what I claim and desire by Letters Patent to secure is:—

1. In a paper file, the combination of a mounting, a series of overlapping sheets, a series of sheet-holders detachably secured to said sheets, respectively, and a bar extending transversely of said sheet-holders between their ends and securing them to said mounting, said bar being movable relatively to said mounting to release said sheet-holders and said mounting presenting a guide which guides said bar in its movement.

2. In a paper file, the combination of a mounting, a series of overlapping sheets, a series of sheet-holders which hold said sheets, respectively, and a bar in said mounting and lengthwise slidably transversely of said sheet-holders into and out of sheet-holder locking position.

3. In a paper file, the combination of a series of sheet-holders, a series of overlapping sheets detachably held by said sheet-holders and a support for said sheet-holders, all cooperatively constructed and arranged to prevent removal of said sheets from said sheet-holders while said sheet-holders remain attached to said support, and means normally to prevent removal of said sheet-holders from said support, said means including a bar approximately parallel with said sheets and lengthwise movable transversely of said sheet-holders in a path approximately parallel with said sheets.

4. In a paper file, the combination of a series of sheet-holders, a series of overlapping sheets detachably held by said sheet-holders and a support for said sheet-holders, all cooperatively constructed and arranged to prevent removal of said sheets from said sheet-holders while said sheet-holders remain attached to said support, and means normally to prevent removal of said sheet-holders from said support, said means including a bar approximately parallel with said sheets and lengthwise movable transversely of said sheet-holders, and a lock by means of which said bar may be locked.

5. In a paper file, the combination of a series of sheet-holders, a series of overlapping sheets detachably held by said sheet-holders and a support for said sheet-holders, all cooperatively constructed and arranged to prevent removal of said sheets from said

sheet-holders while said sheet-holders remain attached to said support, and means normally to prevent removal of said sheet-holders from said support, said means including a bar approximately parallel with said sheets and extending transversely of said sheet-holders approximately parallel with said sheets, said sheet-holders having portions between said bar and said support and substantially covered by said sheets.

6. In a paper file, the combination of a series of sheet-holders, a series of overlapping sheets detachably held by said sheet-holders and a support for said sheet-holders, all cooperatively constructed and arranged to prevent removal of said sheets from said sheet-holders while said sheet-holders remain attached to said support, and means normally to prevent removal of said sheet-holders from said support, said means including a bar approximately parallel with said sheets and lengthwise movable transversely of said sheet-holders and withdrawable from said support in a path approximately parallel with said sheets.

7. In a paper file, the combination of a series of sheet-holders, a series of overlapping sheets detachably held by said sheet-holders and a support for said sheet-holders, all cooperatively constructed and arranged to prevent removal of said sheets from said sheet-holders while said sheet-holders remain attached to said support, and means normally to prevent removal of said sheet-holders from said support, said means including a bar approximately parallel with said sheets and lengthwise movable transversely of said sheet-holders in a path approximately parallel with said sheets, and a lock having a bolt movable into and out of the path of a portion of said bar.

8. In a paper file, the combination of a support having lateral guides, a series of sheets, a series of sheet-carriers received by said guides, each sheet being interlocked with its associated sheet-carrier and incapable of being removed therefrom while such sheet carrier remains received by said guides, and sheet carrier-locking means between said guides and normally locking said sheet-carriers to said support.

9. In a paper file, the combination of a panel presenting parallel channels, a series of sheet-carriers having their ends received in said channels, a series of overlapping sheets carried by and having interlocking engagement with said sheet-carriers, respectively, and a locking bar extending transversely of said sheet-carriers between said channels and locking said sheet-carriers to said panel.

10. In a paper file, the combination of a panel presenting parallel channels, a series of sheet-carriers having their ends received in said channels, a series of overlapping sheets carried by and having interlocking engage-

ment with said sheet-carriers, respectively, a lengthwise-movable locking bar extending transversely of said sheet-carriers between said channels and locking said sheet-carriers to said panel, and a lock having a member movable into and out of the path of a part of said bar.

11. In a paper file, the combination of a support presenting parallel channels, a series of sheets, and a series of sheet-holders having their ends received in said channels, all cooperatively arranged to prevent removal of said sheets from said sheet-holders while said sheet-holders remain attached to said support, each sheet-holder having a portion offset toward said support and having means cooperating with said support to maintain said offset portions in adjacent relationship with said support, and means normally to prevent removal of said sheet-holders from said support, the last-mentioned means including a bar extending transversely of said sheet-holders and received in said offset portions.

12. In a paper file, the combination of a support presenting parallel channels, a series of sheets provided with perforations, and a series of sheet-holders comprising resilient wires received in the perforations of their respective sheets, said sheet-holders having their ends received in said channels, all cooperatively arranged to prevent removal of said sheets from said sheet-holders while said sheet-holders remain attached to said support, each sheet-holder having a portion offset toward said support and having means cooperating with said support to maintain said offset portions in adjacent relationship with said support, and means normally to prevent removal of said sheet-holders from said support, the last-mentioned means including a bar extending transversely of said sheet-holders and received in said offset portions.

13. In a paper file, the combination of a support presenting parallel channels, a series of sheets, and a series of sheet-holders having their ends received in said channels, all cooperatively arranged to prevent removal of said sheets from said sheet-holders while said sheet-holders remain attached to said support, each sheet-holder having a portion offset toward said support and having means cooperating with said support to prevent rotation of said sheet-holders about longitudinal axes, and means normally to prevent removal of said sheet-holders from said support, the last-mentioned means including a bar extending transversely of said sheet-holders and received in said offset portions.

14. In a paper file, the combination of a support presenting parallel channels, a series of folded sheets provided with perforations adjacent their folds, and a series of sheet-holders received in the folds and in the per-

forations of their respective sheets, said sheet-holders having their ends received in said channels, all cooperatively arranged to prevent removal of said sheets from said sheet-holders while said sheet-holders remain attached to said support, each sheet-holder having a portion offset toward said support and having means cooperating with said support to prevent rotation of said sheet-holder about its longitudinal axis, and means normally to prevent removal of said sheet-holders from said support, the last-mentioned means including a bar extending transversely of said sheet-holders and received in said offset portions.

In testimony whereof, I have signed my name to this specification.

RAYMOND C. FINCH.
